UNITED STATES PATENT OFFICE

2,591,109

REFRIGERANT EVAPORATOR

James O. Wade, Adrian, Mich., assignor to Bohn
Aluminum & Brass Corporation, Detroit, Mich.,
a corporation of Michigan

Application July 15, 1948, Serial No. 38,770

2 Claims. (Cl. 62—126)

1

This invention relates to an improved evaporator for a refrigerating unit.

The invention relates to the type of evaporator in which metal tubes are brazed to a metal sheet, as for example in the patent to McCullough et al. 2,359,926. According to the present invention a plurality of tubes and a plurality of headers are brazed to a metal sheet with their interiors interconnected to form a fluid-tight assembly with inlet and outlet openings.

A particular feature of the invention resides in the fact that the accumulating header is inserted in a slot formed in the sheet, this arrangement providing for a neat and rigid mounting of the accumulating header.

An additional feature of the invention resides in the fact that the distributing header is formed from a piece of tubing which has its ends collapsed, a fluid-tight joint at the collapsed ends being produced by causing brazing compound to run between the meeting walls of the tube at the same time the parts are brazed to the sheet.

Other objects and advantages of the invention will become apparent as the description proceeds.

Although preferred forms of the invention are disclosed herein for the purpose of illustration, it should be understood that various changes may be made without departing from the spirit of the invention as herein set forth and claimed.

In the drawings:

Fig. 1 is a perspective view of the bottom and the accumulator end of an evaporator which incorporates the invention.

Fig. 2 is a perspective view of the device of Fig. 1 but showing the top and opposite end.

Fig. 3 is a perspective partly in phantom showing a modified structure.

Fig. 4 is a fragmentary sectional view of part of the structure of Fig. 3.

Fig. 5 is a fragmentary section taken on the line 5—5 of Fig. 3.

Figure 6 is a fragmentary sectional view of part of the distributing header.

Referring to the drawings in greater detail, Figs. 1 and 2 illustrate an evaporator in which a series tube 10, a distributing header 11, parallel tubes 12 and an accumulating header 13 are all brazed to a sheet 14.

In the particular example illustrated in Figs. 1 and 2 the series tube 10 is bent sinuously so as to cover the top of the evaporator, then passes around a corner and is bent sinuously so as to cover one side of the evaporator and part of the bottom. The series tube then discharges into the distributing header 11 which is located at

2

about the middle of the bottom wall of the evaporator. A plurality of parallel tubes 12 extend from the distributing header across the bottom wall of the evaporator and up a side wall to discharge into the accumulating header 13. It will be understood that liquid refrigerant is supplied at the inlet end 15 of the tube 10, and that gaseous refrigerant is withdrawn from the return line 16 connected to the accumulating header.

10 The invention is not confined to the use of any particular material but a preferred material is commercially pure aluminum for all of the parts previously described. Preferably the sheet 14 is a sheet of commercially pure aluminum clad on one side with a coating of a brazing alloy formed of aluminum with a small percentage of silicon, for example 5% of silicon. This aluminum-silicon alloy has a melting point somewhat lower than that of the commercially pure aluminum.

15 20 As used herein the term "aluminum material" includes aluminum alloys as well as commercially pure aluminum.

In manufacturing the evaporator the sheet 14 is originally in flat condition. The various tubes 25 and headers are formed as shown in the drawings and placed on the clad side of flat sheet 14. The assembly is then passed through a brazing furnace and raised to a temperature at which the brazing alloy melts and brazes all of the parts 30 into a single, unitary aluminum structure. After the brazing operation the sheet 14 is bent up into its final shape.

As clearly shown in Figs. 1 and 6 the distributing header 11 is formed from a piece of tubing 35 slightly larger in diameter than the tubes 10 and 12. The opposite ends of header 11 are closed by flattening down the tubing until its inside walls meet and making a saw cut 17 through the upper wall of the tubing at the flattened portion. An extra amount of brazing material may be inserted in the saw cut 17 to insure a fluid-tight seal of these end joints as the result of the brazing operation.

As shown in Fig. 4 the end of tube 10 is reduced 45 in size, i. e., tapered down, inserted in a hole of corresponding size formed in the wall of header 11, and brazed in place.

The parallel tubes 12 are connected to header 50 55 11 in a similar manner but their ends are reduced to a smaller diameter than the end of tube 10. The outlet ends of the parallel tubes 12 are secured into openings formed in the wall of accumulating header 13.

In order to permit the tubes 12 to fit flat against the sheet 14 throughout their length, and to pro-

vide a firm and neat mounting, the accumulating header 13 fits snugly into a slot of corresponding shape cut entirely through sheet 14. If desired an additional amount of brazing material may be supplied around the header 13 in order to provide a strong joint. The ends of header 13 are closed by cup-shaped disks in a well-known manner. The return line 16 is secured to the header 13 in a manner similar to the tube 12, as illustrated in Fig. 4.

It will be understood that all of the parts are formed in the manner previously described, assembled in their respective positions, and any necessary additional brazing material is put in place before the assembly is passed through the brazing oven.

It should be understood that the invention can be adapted to a wide variety of evaporators. The example of Figs. 3 and 5 illustrates a form in which the series tube 10 first passes across the underside of a shelf 18, then passes through the side wall of the evaporator and continues over the outside of the evaporator in the manner previously described. In constructing an evaporator as shown in Fig. 3 the shelf with its attached tubing can be brazed together separately from the main body of the evaporator and the separate pieces of tubing 10 can then be torch-brazed to form a single continuous tube 10.

The advantages of this invention in forming a simple and efficient evaporator will be apparent to those skilled in the art.

I claim:

1. An evaporator for a refrigeration system which comprises a sheet of metal, an elongated tube with closed ends forming a suction header,

a plurality of tubes communicating with the header, each of the tubes being secured to the sheet throughout its length, the metal sheet having an elongated slot cut therethrough, the suction header fitting closely into said slot and being secured to the sides of the slot.

2. An evaporator for a refrigeration system which comprises a sheet of metal, a refrigerant-carrying tube in contact with the metal sheet to cool the metal sheet, a hollow, elongated, cylindrical header member of larger diameter than the refrigerant-carrying tube and in communication with the refrigerant-carrying tube, the metal sheet having an elongated slot cut therethrough, the cylindrical header member fitting closely into said slot and being secured to the sides of the slot.

JAMES O. WADE.
